UNITED STATES PATENT OFFICE.

FREDERICK A. VOOS, OF NEWARK, NEW JERSEY, ASSIGNOR TO WESTERN ELECTRIC COMPANY, INCORPORATED, OF NEW YORK, N. Y., A CORPORATION OF NEW YORK.

MEASURING SYRINGE.

Application filed August 6, 1923. Serial No. 655,809.

This invention relates to nozzles and more particularly to nozzles suitable for use on syringes and similar articles.

The object of the invention is to provide means for ejecting small quantities of fluid from a container and for accurately controlling the amount to be ejected.

A feature of the invention is the provision of a measuring nozzle for a fluid container.

A further feature of the invention lies in the use of a needle valve to control the quantity of fluid ejected by the nozzle.

A still further feature lies in the means for operating the needle valve under pressure to eject fluid from the nozzle.

These and other features of the invention will be apparent from a consideration of the accompanying drawing and description together with the appended claims.

In the drawing, Fig. 1 shows a general view of a syringe equipped with the nozzle of the invention. Fig. 2 shows an enlarged view of the nozzle with a skeleton showing 25 of the needle valve. Fig. 3 shows a cross-section of the nozzle with the piston of the valve in position for ejection of fluid. Fig. 4 shows a portion of a modified form of the valve.

The nozzle consists of a short straight tube 1 which decreases rather abruptly to a tapering section 3.

The straight section is equipped with an interior screw thread 4 for attachment to 35 the syringe 5 and carries an integral knurled ring 2 which serves for a grip in screwing the nozzle on to the syringe. Between the screw threads and the tapering tube is a cylindrical chamber 6. The tapered tube has 40 its bore made up of several straight sections of successively smaller diameter forming shoulders such as 7 and 8.

In this tube is placed a tapering rod or 45 needle 9 provided with a cylindrical head 10. This head moves freely in the chamber 6 but is large enough to cover the opening 11 at the larger end of tube 3 and also to close the opening 12 in the threaded end of the 50 syringe 5. The needle is so tapered that when in its extreme forward position, as shown in Fig. 2, it closes the tube at the shoulder 8 acting as a valve to prevent any 55 contents of the nozzle from escaping.

A modification of the nozzle is shown in 55 Fig. 4. In this case the tube 20 has a uni-

formly tapered bore while the needle is straight for the greater part of its length, but has a taper, somewhat greater than that of the tube, near the tip, forming an angle or shoulder 22. This shoulder seats against 60 the inner surface of the tube and acts as the valve in this form of the invention.

The purpose of the various features of the nozzle will be more clearly understood from a description of the method of operation. The syringe itself may be of any well known type having a threaded outlet such as 18. The piston is slipped inside the tube and the nozzle screwed on to the syringe, a gasket 13 being provided to make a fluid- 70 tight joint.

The syringe having been filled with the fluid to be used, pressure is applied to the main piston 14 by means of the rings 15. The pressure on the fluid will be transmitted 75 to the head 10 which will be forced forward and the shaft seated on the shoulder 8 as shown in Fig. 2. Still maintaining the pressure on piston 14, the tip 16 of the needle 9 is then placed against the surface, such as 80 17, to which the fluid is to be applied and the needle forced back into the tube. This action brings the needle head 10 against the threaded outlet 18 of the syringe closing the opening therein. At the same time, the 85 fluid which, under the pressure on piston 14, has filled the chamber 6 and the tube 3 as far as the shoulder, is forced around the head 10 and the needle 9 out on the surface 90 17.

It has been found that this arrangement affords a method for applying definite small amounts of fluid to a surface, varying with the pressure applied to the rings 15. The pressure applied to the piston 14 by means 95 of the rings 15 is transmitted to the fluid in the chamber 6 and through it to the walls of the chamber and the head 10 of the needle 9. As soon as the tip 16 is applied to a surface and the head 10 is lifted from the opening 11, the pressure on the fluid gives to the fluid a velocity varying with such pressure. The time consumed by the needle in moving from its forward to its rearward position is extremely small and only a small quantity of liquid has time to leave the nozzle before the opening in the syringe is closed by the head 10. The greater the pressure on the fluid the greater the velocity with which it moves from chamber 6 into the tube 3 and 105 110

the greater the quantity of liquid ejected. Thus by varying the pressure applied to the rings 15 the quantity of fluid forced out of the syringe may be very closely controlled and once the desired pressure has been determined a uniform quantity of fluid can be ejected at each application of the syringe.

As soon as the nozzle is removed from surface 17, the pressure on the rings 15 and the piston 14 will cause the needle 9 to return to its forward position as shown in Fig. 2.

The nozzle which forms the subject of this invention, was developed for the purpose of applying a small but controllable quantity of lubricant directly to the surface to be lubricated. However, modifications to adapt the nozzle for surface applications of other fluids are obvious and the claims have not been limited to a lubricating device.

What is claimed is:

1. A nozzle comprising an inlet tube, a cylindrical chamber, an outlet tube, interior shoulders in said outlet tube, a piston comprising a head and a shaft, said head movably held in said chamber, said shaft so tapered as to seat on one or more of said shoulders, means for applying pressure to said head to cause said shaft to close said outlet tube, and means to move said piston against said pressure to close said inlet tube and force a portion of the contents of said chamber out of said outlet tube.

2. In combination, a syringe, a nozzle valve comprising a piston having a shaft adapted in one position of said piston to close said nozzle and a head adapted in another position of said piston to close the outlet of said syringe, a portion of said shaft projecting beyond said nozzle by means of

which said piston is moved from said first position to said second position.

3. The combination of a syringe, a nozzle for said syringe and a valve in said nozzle comprising shoulders on the interior of said nozzle, and a needle seated on one or more of said shoulders to close said nozzle, and projecting beyond the tip of the nozzle, whereby the application of said nozzle to a surface opens said valve.

4. The combination of a syringe, a nozzle for said syringe and a valve in said nozzle comprising shoulders on the inner surface of said nozzle, a needle seated on said shoulders to close said nozzle and projecting beyond the tip of the nozzle, a head on said needle, the projection of said needle serving to open said valve and cause said head to close said syringe when said nozzle is applied to a surface.

5. A fluid applicator comprising a container, an outlet for said container, means for applying pressure to said outlet, a nozzle, means for closing said nozzle when pressure is applied to said outlet, and means for closing said outlet and forcing a small quantity of liquid out of said nozzle when applied to a surface.

6. In a fluid applicator, a reservoir, a measuring chamber, means to force fluid under pressure from said reservoir into said measuring chamber, means to simultaneously prevent further flow from said reservoir to said measuring chamber and to release the fluid from said measuring chamber, said fluid being released under a pressure which is a function of the pressure used to force fluid into said measuring chamber.

In witness whereof, I hereunto subscribe my name this 2 day of August, A. D., 1923.

FREDERICK A. VOOS.
